(57) **CLAIM**

The ornamental design for a heart-shaped cup, as shown and described.

DESCRIPTION

FIG. 1 is a top rear perspective view of a heart-shaped cup showing my new design;

FIG. 2 is a bottom perspective view thereof;

FIG. 3 is a bottom left elevational view thereof;

FIG. 4 is bottom right elevational view thereof;

FIG. 5 is a bottom front perspective view thereof;

FIG. 6 is a top view thereof;

FIG. 7 is a bottom view thereof;

FIG. 8 is a right side view thereof;

FIG. 9 is a left side view thereof;

FIG. 10 is the rear view thereof;

FIG. 11 is the front view thereof; and,

FIG. 12 is a cross-sectional side view thereof.

The shading lines shown on the drawings depict portions of a heart-shaped cup that form no part of the claimed design.
